M. WEINSCHENK & W. BOLDENWECK.
MEDAL.

No. 20,195.

Patented Oct. 7, 1890.

UNITED STATES PATENT OFFICE.

MAIER WEINSCHIENK AND WILLIAM BOLDENWECK, OF CHICAGO, ILLINOIS.

DESIGN FOR A MEDAL.

SPECIFICATION forming part of Design No. 20,195, dated October 7, 1890.

Application filed July 25, 1890. Serial No. 359,969. Term of patent 3½ years.

To all whom it may concern:

Be it known that we, MAIER WEINSCHENK and WILLIAM BOLDENWECK, citizens of the United States, residing at Chicago, in the county of Cook and State of Illinois, have invented and produced a new and original Design for Medals, of which the following is a specification, reference being had to the accompanying drawing, forming a part thereof.

Our invention relates to a design for one face of a medal.

The drawing represents a front view of the design and illustrates two cardinal events in the history of America. The upper portion of the drawing represents the first cardinal event, viz: the discovery of America by Columbus. The lower portion of the drawing represents the second cardinal event, viz: the landing of the Pilgrims at Plymouth. Between these pictorial representations is that of a ribbon or scroll.

The leading feature in our design consists in the pictorial representation of the above-named two cardinal historical events, one above the other, with an intermediate ribbon or scroll.

What we claim is—

The design herein shown and described for a medal, the same comprising a pictorial representation upon the upper portion of one face of the medal of the discovery of America by Columbus, a pictorial representation upon the lower portion of the said face of the landing of the Pilgrims, and an intermediate pictorial representation of a ribbon or scroll, as set forth.

MAIER WEINSCHENK.
WILLIAM BOLDENWECK.
